(57) **CLAIM**

The ornamental design for a medical implant communication device, as shown and described.

DESCRIPTION

FIG. 1 is a front perspective view showing the front, top and right side of a medical implant communication device according to our new design;

FIG. 2 is a rear perspective view;

FIG. 3 is a left side elevational view;

FIG. 4 is a right side elevational view;

FIG. 5 is an enlarged top plan view; and,

FIG. 6 is an enlarged bottom plan view thereof.

The cord is shown broken away in the middle in FIGS. 1-4 to indicate indeterminate length.
